UNITED STATES PATENT OFFICE

JOSEPH E. PRIMAKOW, OF MILWAUKEE, WISCONSIN

DESIGN FOR A LIGHTING FIXTURE

Application filed April 17, 1931. Serial No. 39,525. Term of patent 3½ years.

To all whom it may concern:

Be it known that I, JOSEPH E. PRIMAKOW, a citizen of the United States, residing at Milwaukee, in the county of Milwaukee and State of Wisconsin, have invented a new, original and ornamental Design for Lighting Fixtures, of which the following is a specification, reference being had to the accompanying drawing forming part thereof.

The figure shown is a perspective view of the lighting fixture. The opposite side of the article is substantially the same as the side shown.

I claim:

The ornamental design for a lighting fixture substantially as shown and described.

In testimony whereof I affix my signature at 6083 Plankinton Building, Milwaukee, Wisconsin.

JOSEPH E. PRIMAKOW.
